(57) **CLAIM**

The ornamental design for lighted zipper tag, as shown and described.

DESCRIPTION

FIG. 1 is a frontward/topside perspective view of the lighted zipper tag device according to the present design;

FIG. 2 is a rearward/bottomside perspective view of the lighted zipper tag device of FIG. 1 according to the present design;

FIG. 3 is a top plan view thereof;

FIG. 4 is a left side, elevational view, the right side being a mirror image thereof;

FIG. 5 is a front elevation view thereof;

FIG. 6 is a rear elevation view thereof; and,

FIG. 7 is a bottom plan view thereof.

The broken lines shown in the drawings are included for the purpose of illustrating environmental structures and form no part of the claimed design.
